UNITED STATES PATENT OFFICE.

ANNA O'BRIEN, OF NEW YORK, N. Y.

HAIR CURLER.

Application filed November 17, 1923. Serial No. 675,257.

The present invention relates to hair curlers of the type commonly used with or without heat to effect a curling or waving by winding the hair thereon and leaving it for 5 a few hours or until the desired curl or wave is produced.

The object of the invention is to provide an improved curler and further to provide a curler which can be cheaply and expeditiously manufactured. The invention in its 10 preferred form provides a heating means which may be used or not as desired.

The invention will be better understood from a description of a particular illustrative embodiment thereof. For the purpose of this description reference should be had to the accompanying drawing forming a part hereof and in which—

Figure 1 is a view of a blank from which 20 a curler embodying the principles of the invention is to be formed.

Figure 2 is a side view of the curler after the blank has been bent to final form, showing the clamping member in open position.

Figure 3 is a similar view showing the curler in closed position indicating in dotted lines the preferred arrangement of the hair thereon when the device is in use and showing also the heating element introduced into 30 the tubular body member of the curler.

Figure 4 is a view showing the heating element removed.

Figure 5 is a cross-sectional view taken on the line 4—4 of Figure 3.

The curler shown for the purpose of illustration is designed to be made from sheet metal having preferably a sufficient spring quality so that the clamping member may stand normally a substantial distance away 35 from the body member while being readily moved to and secured in clamping relation against the same. The blank is wider toward one end to form a tubular body member and narrower toward the other end to 40 form a clamping member. As shown the blank 5 is formed with preferably similar wings 6 on opposite sides which wings are bent to form a substantially cylindrical tubular body member. The narrower portion 45

50 of the blank is folded back to lie along the body member and form a clamping member cooperating with the body member to secure the hair. The bend of the clamping member is preferably such as to form a substantially close loop 9 to receive and retain an elastic band 10. The free end of the clamping

member is formed to provide a hook 11 engageable with a tongue 12 on the free end of the body member. The hook element as shown is preferably formed upon the clamping member rather than on the body member in order that the body member may be so formed as to permit the hair to be easily removed therefrom. The tongue 12 furthermore is preferably bent slightly backward so that the hook 11 will be positioned away from the center of the tubular body member when in clamped interlocking relation in order that a heating element may be easily introduced from this end if desired. The loop 9 is also so formed as to permit the introduction of the heating element 13 from that end but it may further be so formed as to frictionally engage and therefore retain the heating element in position in the tubular body member as indicated at 14 if desired. In the preferred manner of use of the device the end of a strand of hair is clamped between the two members and the free ends are interengaged, then the hair 50 is rolled with or without a twist around the whole device. The elastic band 10 may then be connected to the opposite end of the device to hold the hair in curling position. The shape of the free end of the body member may be made such that the elastic band 55 may be simply engaged over the end thereof as indicated at 15, Figure 2. If desired, however, the free end of the clamping member may be reversely bent to provide an outwardly open recess or notch 16 to receive the band 10.

The shape of the body member is such that the hair will be given as nearly a true or uniform curl or wave as possible. To this 65 end the body member is made substantially cylindrical in form but is preferably slightly flattened where the clamping member lies against it and the clamping member is preferably slightly curved in cross section as indicated at 20. By this arrangement the curl at the end of the hair is substantially the same as that at the other parts thus avoiding the sharp curl at the end which is caused if the hair is given a short bend 100 immediately adjacent the point where it is clamped when for example the hair is clamped between and curled around flat members. Furthermore the curler as a whole when closed is still substantially cylindrical so that the curl or wave throughout 105 the length of the strand is uniform and even.

The curvature of the clamping member transversely of its length should not be made sufficient to cause a loss of the flexibility thereof. In Figures 2 and 3 this curvature is indicated as extending the greater portion of the length of the clamping member but it should not extend around the loop 9 because of the interference with the flexibility of the device and it need not be continued around the hooked end 11, 16.

The heating element consists simply of a rod of suitable shape for insertion within the tubular member and is provided with a suitable handle 21 of wood or other heat insulating material.

The end 22 of the tubular body member is preferably formed at a sufficient angle so that it will not tend to catch in the hair during removal.

The device in its preferred form as described can be cheaply and expeditiously manufactured by simple stamping and bending operations from relatively inexpensive

material such as steel or brass and is durable and effective in use.

25

I claim:

A hair curler of the character described comprising a sheet metal blank having lateral wings along substantially one half its length bent together to form a substantially cylindrical tubular body member and a spring strip bent to form at one end a band receiving loop and at the other end a hook and an outwardly open band receiving recess, the body member being formed with a projection engageable with said hook to hold the members in clamping relation and an elastic band extending through said loop engageable with said outwardly open recess substantially as and for the purpose described.

In testimony whereof, I have signed my name to this specification this 7th day of November, 1923.

ANNA O'BRIEN.
